CLAIM

The ornamental design for a portable storage carrier for vehicles, as shown and described.

DESCRIPTION

FIG. 1 is a front elevational view of the portable storage carrier for vehicles showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a perspective view thereof.

The broken lines shown in FIG. 5 are for illustrative purposes only and form no part of the claimed design.
